UNITED STATES PATENT OFFICE.

CHARLES W. MOTTS, OF ATCHISON, KANSAS, ASSIGNEE TO HENRY WEIS MANUFACTURING COMPANY, OF KANSAS CITY, MISSOURI, A CORPORATION OF MISSOURI.

TOILET-PARTITION.

1,256,354.

Specification of Letters Patent. Patented Feb. 12, 1918.

Application filed April 11, 1917. Serial No. 161,170.

To all whom it may concern:

Be it known that I, CHARLES W. MOTTS, a citizen of the United States, residing at Atchison, in the county of Atchison and State of Kansas, have invented certain new and useful Improvements in Toilet-Partitions; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to toilet partitions and has for its principal object to provide a sheet metal structure which is simple and substantial in construction, slightly in appearance and comprises means whereby the partition supporting members may be adjusted to fit uneven floor surfaces.

20 In accomplishing this object, I have provided improved details of structure the preferred forms of which are illustrated in the accompanying drawings, wherein:

Figure I is a back perspective view of a toilet provided with partitions constructed according to the present invention.

Fig. II is a detail perspective view of a portion of a partition wall illustrating its locking connection with a partition standard and the adjustable shoe at the base of the standard.

Fig. III is a vertical section through a standard, illustrating its mounting in a base shoe.

Referring more in detail to the drawings:

1 designates a toilet constructed according to the present invention, comprising vertically spaced partitions 2 which are raised from the floor and extend forwardly from a wall or other support (not shown), and are mounted at their forward ends in vertical supporting standards 3.

45 Each of the partition walls 2 comprises a sheet metal plate, provided at its rear vertical edge with a laterally turned flange 5 provided with apertures 6 for receiving bolts or screws for anchoring the plates to a supporting wall, and along the top and bottom horizontal edges of the plate are integrally formed rails 8 of triangular cross section and having horizontal base portions 9 which add stiffness to the partition plate

and enhance the appearance of the finished 55 structure.

The standards 3 initially comprise rectangular sheet metal strips, which are formed in suitable machines to tubular standards of rectangular cross section. 60

The forward ends of the rails 8, at the edges of the partition wall, are provided with slots 11, forming anchor heads 12 and the edges of the tubular standard are pressed into said slots, to inclose the heads 12 within the standard and anchor the partition wall thereto; the edges of the standard being drawn together and welded above and below the partition wall to anchor the latter to the standard and hold the end of the partition wall flush against the outer face thereof. 70

The standards 3 are joined rigidly together at their upper ends and to the supporting wall by means of ornamental fittings 14, and the lower ends are movably mounted in base shoes 15 to effect adjustment and anchoring of the partition parts to an uneven floor surface. 75

The shoes 15 are of substantial metal construction and comprise flared base plates 16 through which bolts 17 may be projected downwardly to anchor the shoe to a floor, and comprise neck portions 18 within which the lower ends of the standards 3 may be 85 adjustably mounted.

At the back side of the neck portions 18 are upwardly extended ears 19 which lie adjacent the standards and carry screw bolts 20, the shanks 21 of which project inwardly 90 and are slidable within vertical slots 22 that extend upwardly from the base ends of the standards.

The bolts 20 carry nuts 23 within the standards which may be tightened against 95 the standards to lock the latter at vertically adjusted positions within the shoe necks.

Assuming that the parts are so constructed, in assembling the partition the sheet metal parts, including the previously cut 100 standards with the partition walls anchored therein as described, together with the ornamental fittings and the base shoe, are furnished from the factory and the parts erected in a building by securing the flanged portions 5 of the partitions to a supporting wall by bolts or screws projected into the wall through the flange apertures 6, and the 105

lower ends of the standards are mounted on the shoes 15 and by bolts 17, extended through the bases thereof.

Should the floor surface be uneven as is usually the case, if of cement construction, there will be a necessary adjustment of the base shoes 15 on the standards 3 so that solid mountings may be had for the ends of the standard without drawing the parts out of alinement; this adjustment being accomplished by loosening the screw bolts 20 so that the standards may be free to move within the shoe necks until perfect alinement of the parts is effected. The bolts are then tightened to clamp the standards in the shoes at such adjusted positions and provide a rigid and substantial structure.

It is apparent that this construction affords a durable and sightly compartment, and the standards may be adjusted in their anchor members to effect perfect alinement of all the parts regardless of uneven floor surfaces.

Having thus described my invention, what I claim as new therein, and desire to secure by Letters Patent, is:

1. A toilet partition comprising a side member having an anchoring flange at one end and a supporting standard at its opposite end, a floor shoe for slidably receiving the lower end of said standard and means for securing the standard within the shoe.

2. A toilet partition comprising a side member having an anchoring flange at one end and a supporting standard at its opposite end, a floor shoe for slidably receiving the lower end of said standard, means for securing the standard within the shoe and means for anchoring the shoe to the floor.

3. A toilet partition comprising in combination with a floor shoe having an upwardly extended shank, a side member having an anchoring flange at one end, a tubular supporting standard at the opposite end of side member having a vertically slotted end adjustably seated in said floor shoe, a bolt projecting from said neck through the slot in said standard and a nut on said bolt within the standard for an-

choring the standard to the neck of the 50 shoe.

4. In a toilet partition, a tubular standard having a vertical slot at its lower end, a floor shoe, having a flared base portion and an extended neck, for receiving the 55 slotted end of said standard, a bolt projected through a wall of said neck and slideable in said standard slot, a nut on said bolt within the standard whereby said standard may be anchored within the said shoe and 60 means for anchoring shoe to a floor.

5. In a toilet partition, a tubular standard having a vertical slot opening to the lower end thereof, a floor shoe comprising a flared base portion and a tubular neck for 65 receiving the slotted end of said standard, an extended, apertured ear on said neck adapted to lie along the slotted wall of the standard, a bolt projected through said ear aperture and standard slot and a nut on said 70 bolt adapted for tightening against said standard to lock the latter in an adjusted position in said shoe.

6. In a toilet partition, a tubular standard having a vertical slot at the lower end 75 thereof, a floor shoe comprising a flared base portion provided with a central aperture and a tubular neck for receiving the slotted end of said standard, an extended, apertured ear on said neck adapted to lie 80 along the slotted wall of the standard, a bolt projected through said ear aperture and standard slot, a nut on said bolt adapted for tightening against said standard to lock the latter in an adjusted position in said shoe, 85 and a bolt extended through said base aperture to anchor said shoe to the floor.

7. In a partition, a slotted standard, and a partition member comprising an enlarged edge portion having vertical slots forming 90 a head integral with said edge portion, the body and slotted edge portion of the partition seating in the standard slot with the integral head located within the interior of the standard to anchor the partition to the 95 standard.

In testimony whereof I affix my signature.
CHARLES W. MOTTS.
